UNITED STATES PATENT OFFICE.

SPAULDING CUTLER, OF CINCINNATI, ASSIGNOR OF ONE-HALF TO CLINTON D. FIRESTONE, OF COLUMBUS, OHIO.

BUTTON-HOLE ATTACHMENT FOR SEWING-MACHINES.

SPECIFICATION forming part of Letters Patent No. 268,002, dated November 28, 1882.

Application filed June 16, 1879.

To all whom it may concern:

Be it known that I, SPAULDING CUTLER, of the city of Cincinnati, in the county of Hamilton and State of Ohio, have invented certain new and useful Improvements in Button-Hole Attachments for Sewing-Machines, of which the following is a specification.

Attachments for sewing and binding button-holes have heretofore been very complicated, and prominent among their defects has been the lack of machinery to properly finish the button-hole—that is, to stitch across the acute end of the hole a few times in order to furnish a neat finish, as well as strengthen the binding. This finishing is always seen in hand-made button-holes. To obviate these defects and shortcomings I have invented a button-hole attachment for sewing-machines, more fully described and claimed below.

In the accompanying drawings, forming a part of this specification, Figure 1, Sheet 1, is a perspective view of my improved button-hole attachment, taken from the rear side, or that side to which the operating-lever is secured. Fig. 2, Sheet 2, is a side elevation of the devices which give the various movements to the clamping feed-plate, and are secured to what I term the "top plate" of the attachment, the view being taken from the front side of the machine. Fig. 3, Sheet 2, is an end elevation of the devices shown in Fig. 2, taken from the end that appears to the right hand in said figure. Fig. 4, Sheet 2, is an enlarged sectional view taken on the line X-X, Fig. 3, and looking from the front side of the attachment. Fig. 5, Sheet 2, is a longitudinal sectional elevation of the cloth-clamping feed-plate minus the end by which it is pivoted to the base-plate of the attachment. Fig. 6, Sheet 2, is a plan view of the end of the clamping feed-plate by which it is operated, showing the rack with which the operating-pinion engages. Fig. 7, Sheet 2, is a plan view of the reciprocating box and dog, through which rotary motion is imparted to the pinion that operates the clamping-lever. Fig. 8, Sheet 2, is a partial elevation of the mechanism for connecting and disconnecting the clamping feed-plate with the mechanism that vibrates it laterally. Fig. 9, Sheet 3, is an enlarged sectional elevation taken on line Y-Y, Fig. 3, showing the mech-

anism by which the reciprocating motion of the main operating-lever is, during transmission, converted into rotary motion. Fig. 9^a is a horizontal section taken at the dotted line Z of Fig. 9, to show the notches o³ in cam O. Fig. 10, Sheet 3, is an enlarged sectional view of the device for adjusting the attachment upon needle-plates of various heights. Fig. 11, Sheet 3, is a perspective view of the clamping-jaw, also employed to secure the attachment upon the machine. Fig. 12, Sheet 3, is a plan view, illustrating the manner in which the clamping-jaw secures the attachment to the machine. Fig. 13, Sheet 3, is a plan view of a modified form of mechanism for operating the clamping feed-plate, showing the plate of the attachment to which it is secured. Fig. 14, Sheet 3, is a sectional elevation on line Z-Z, Fig. 13, looking toward the rear end of the attachment. Fig. 15, Sheet 3, is a detail side elevation of the means for imparting motion from the main operating-lever to the mechanism shown in Figs. 13 and 14. Fig. 16, Sheet 3, is a detail view of the adjustable link that connects the levers through which motion is imparted to the clamping feed-plate-operating pinion in the modified construction. Fig. 17, Sheet 3, is an enlarged section taken on line U-U, Fig. 15. Fig. 18, Sheet 4, is a plan view of the entire attachment. Fig. 19, Sheet 4, is a longitudinal sectional elevation of the entire attachment, taken centrally through bearings of feed-plate-operating spindle, and centrally through the feed-plate itself. Fig. 20, Sheet 4, is an inverted plan view of top plate of the attachment and mechanism for imparting motion to the feed-plate. Fig. 21, Sheet 5, is a plan view of the attachment with the top plate and mechanism secured thereto removed, showing bed-plate, feed-plate, and main operating-lever. Fig. 22, Sheet 5, is an enlarged transverse sectional view of the feed-plate, taken through its rack, and showing the operating-pinion in elevation. Fig. 23, Sheet 5, is a sectional plan view of a modified form of feed-plate-operating mechanism. Fig. 24, Sheet 5, is a longitudinal sectional elevation of the modified form of mechanism shown in Fig. 23, taken on a line through the bearings of the operating-spindle.

In the various figures of the drawings simi-

lar letters are used to designate similar parts.

A is the base-plate of my attachment, and has extending from it a flat bar, A'.

The supporting-plate B, for upholding and maintaining in position the mechanism for laterally and obliquely shifting the feed-plate, is located above the base-plate A, (see Figs. 3, 4, 18, and 19,) and is located over that portion of said plate which is on the left hand in Fig. 1, being supported by the vertical side supports, A⁶.

The feed-plate U, with its appendages, rests upon the plate A and its extension A', being secured to said extension by the screw u, which passes through the slot u', and is screwed into said extension A' at the point shown in Fig. 1. To the other extremity of the feed-plate U is attached the device for receiving the various motions to be imparted to the same. This device consists preferably of three plates screwed together, as shown in Figs. 5 and 6. The bottom plate, u², of these three plates has at its center a solid elevation or raised pattern, u³, of the same shape as the button-hole to be sewed, as shown in Figs. 6 and 21. The second plate, u⁴, is preferably of the same thickness as the elevation or raised pattern u³ of the plate u², having an opening of a similar shape to that of said elevation or raised pattern, and surrounding the same, forming a groove, u⁵, of equal width throughout. The third plate, u⁶, has an opening similar in shape to the opening in the plate u⁴, but of a larger size, and having the teeth u⁷, as shown in Figs. 6 and 21. This third plate is placed upon the plate u⁴ in such a manner that there shall be a space between the points of the teeth of the plate u⁶ and the upper edge of the opening in plate u⁴, and so that this space shall be everywhere the same. These plates are held together and to the feed-plate U by the screws u⁸. A guide-plate, V, is attached to the feed-plate U by a flange, v, and extends vertically upward, having an extension, v', which projects over the top of the plate u⁶, the object of this construction being to make the top of the guide-plate V as long as possible and still economize room. The feed-plate U is provided with an oval slot, U', Figs. 1 and 5, between which and the guide-plate V the screw W is attached to the feed-plate U, extending vertically upward, being surrounded by a spiral spring, X, on which rests the curved clamping-jaw Y, which has an opening through which said screw W passes. A button-hole of proper shape having been cut in the goods, they are passed between the aforesaid feed-plate U and clamping-jaw Y, the latter being screwed down on the goods by the thumb-nut w pressing on the bearing y. The clamping-jaw Y is provided with a button-hole-shaped opening, y', (see Figs. 1, 5, and 21,) surrounding which, on the under surface of the clamping-jaw, is a downwardly-extending flange, y², which fits the opening U' immediately beneath it in the feed-plate U. At one side of the button-hole-shaped

opening y' an index, y³, (see Fig. 1,) is marked upon the upper surface of the clamping-jaw y, to serve as a guide to the eye in adjusting the clamping-jaw to guide the goods so as to finish a button-hole of the desired length.

The extension A' of the plate A (see Fig. 1) is provided with a needle-opening, a³, and an opening, a⁴, for the feed of the sewing-machine to operate in. The opening a³ is always under some portion of the opening y' of the clamping-jaw Y when the attachment is in operating condition. When the attachment is in the position shown in Fig. 1 the needle-arm will be descending, and with the cloth in the aforesaid described position between the feed-plate U and clamping-bar Y, the work of the attachment is accomplished by the continued descending motion of the needle-arm, forcing downward the lever-arm R, which is attached to the inner end of a small rock-shaft supported by the standard Q, attached to the plate A. The lever-arm R, in turn acting upon aforesaid rock-shaft, forces the slide T in a direction from the needle by means of the vibrating arm S, attached to the opposite end of the said rock-shaft, and connected with the slide T by the connecting-rod S', the slide T operating between the flanges a and b' and guide Q', the flange a extending upwardly from the plate A, and the one b' downwardly from the supporting-plate B, and the guide Q' (see Fig. 1) extending from the foot of the standard Q under the plate B, its top being a slight distance below the plate B. The upper part of this slide T has a flange, t, extending inwardly, which rests upon the top of the guide Q', and is provided with teeth which extend inwardly beyond the inner edge of the guide Q', and which mesh with the teeth of the gear n, Figs. 2 and 3, and operate the mechanism above described. The teeth t of the slide T operate the disk N, which in this direction of its motion turns loosely and influences no other part of the attachment. This disk N is centered upon a shaft, m⁴, which extends downwardly from the portion m of the disk M, (see detailed view of Fig. 9,) below the plate B, said disk being provided with the gear n, heretofore referred to. A groove, n', extends diametrically across the under surface of the disk N, and has two sides, as shown in Fig. 2, one of which is vertical and the other oblique, so that the disk serves as a ratchet (as the needle-bar ascends) upon the pin or vertical tooth O², which is set in a recess in and carries with it the cylinder O. (See Fig. 9.) It is kept constantly pressed against the under surface of the disk N by the spring O⁴ coiled around the stem of the vertical tooth, below the head of the latter, and compressed between said head and the bottom of the recess in which the spring is. The cylinder O, being pinned to shaft m⁴ by the pin O', rotates said shaft, and by this means rotates the disk M. This disk M has also a dovetailed groove, m', in which a dovetailed piece, m², slides, and is secured in position by the

set-screw l^2 , which also acts as a pin, passing through the slot l' in the lever L. The cylinder O is prevented from retracting by the tooth P (see Fig. 9) entering the vertical groove O^3 , and kept against the cylinder by a spring or similar means. The rear end of this tooth P plays in a closely-fitting recess in the projection P' , the shank of the tooth playing in the rear portion of the same recess, and is there surrounded by a coiled spring compressed between the head and the end of the recess. The end of the shank closely slides in an opening in projection P' , behind the recess. The cylinder has two grooves, such as O^3 aforesaid, diametrically opposite each other, in its curved surface. The amount of motion which the slide T receives from the levers R and S is such as rotates the disk M exactly half-way around during the upward motion of the needle.

20 A bent lever, L, is fulcrumed to the plate B at the point b^7 . One end of this lever has a closed slot, b' , into which pin l^2 of the disk M works when said disk rotates, Figs. 1, 3, and 18, forcing the arm of the lever L in a direction from the needle, and this motion, being transmitted by the other arm, b^3 , of said lever to the plate C, (by means of the vertical pivot b^4 , projecting upwardly from the plate into a slot in the arm,) forces the said plate C and its fixed appendages to slide in a limited oblique direction upon the plate B, the movement of said plate C being governed by the slots c and pins c' in a direction toward the needle and toward the slide T. This plate C rests upon the supporting-plate B, the two slots c being cut at an angle of about forty-five degrees to the edges of the plate, the pins c' being secured to the plate B and projecting upward through the slots c .

40 Extending above the plate C, and attached thereto, is the bridge C^2 , having a downwardly-extending sleeve, C^3 , with a central orifice, through which passes and snugly fits the stem D. (See Figs. 2, 4, and 19.) This stem D is carried by the plate C, and its projection d^3 , extending below the gear-wheel D^2 , which is on the lower end of the stem, fits closely in the groove u^5 . This stem D extends downward through the bridge C^2 , sleeve C^3 , box F, and sleeve C' , hereinafter described, the lower portion of this stem D being enlarged at a point, as shown, preferably nearly midway between the top of the box F and the under side of the top of the bridge C^2 , in order that the spiral spring d , which surrounds the stem between the under side of the top of the bridge C^2 and the top of the shoulder formed by the aforesaid enlargement of the stem, may impinge against same and force the stem D downward, this stem D (see Fig. 4) being retained in position by the thumb-nut d^4 , preferably bearing on the conical washer d^5 , resting upon the upper side of the lever H, the stem D passing through the slot h^2 (preferably oval) of said lever.

65 The lateral oscillation of the feed-plate U,

by means of which the edge and center of the slot y' are alternately brought over the needle-hole a^3 , is produced in the following manner: The projection d^3 of the stem D, fitting in the slot u^5 , carries the feed-plate U with it in its lateral movements, the feed-plate U being pivoted at u . The stem D in its turn derives its lateral motion from the plate C, to which it is attached. Now, suppose the projection d^3 to be in that portion of the slot u^5 which is farthest from the slide T, the movement of the plate C toward the slide T will carry the stem D, and consequently the plate U, in the same direction, and thus that edge of the slot y' which is farthest from the needle-hole a^3 will be brought toward the needle-hole, and the return motion of the plate C in the opposite direction will bring the center of the slot y' over the needle-hole a^3 .

Beyond the slot l' of the lever L the connecting rod L' is pivoted at b^5 . This lever L, as described, also moves the connecting rod L' in a direction from the needle, drawing the dog G, (see Figs. 1, 4, and 7,) which is attached at its outer end to said rod L' by means of the thumb-nut l^4 , passing through the closed slot b' in said rod in a similar direction.

The dog G, being pivoted in the box F, Fig. 7, has a point, g , adapted to impinge against the periphery of the flange E' of the sleeve E, so that when the dog is operated in this direction (see arrow, Fig. 7) it acts to revolve the sleeve-flange E' and sleeve E in a similar direction, carrying the box F with it. (See Figs. 4 and 7.) This sleeve-flange E' is attached to the upper extremity of the hollow sleeve E, which passes snugly through the downwardly-extending sleeve-axis C' of the plate C. The sleeve-axis C' and its contents operate through the openings b in the plate B. The sleeved flange E' may be provided with an upwardly-extending flange, e , as indicated in Fig. 7, in which case the flange would have to pass through the top of the box F. Rotating the sleeved flange E' rotates the gear D^2 by means of the feather e' , projecting from the interior of the sleeve E, and fitting into the vertical groove d' on the enlarged part of the stem D. This rotation of the gear D^2 forces the feed-plate U toward the needle—that is, the circular end of the slot y' is brought closer to the needle-hole a^3 at the same time that the plate C is moved. The plate C, when moved, swings the lever I on its fulcrum i on the plate B by means of its sleeve-axis C', which passes through the slot i' of said lever I. The lesser diameter of the slot i' is equal to the diameter of the sleeve-axis C', and its larger being greater than the same, so that a lateral motion of the sleeve-axis C' will oscillate said lever I, while a longitudinal motion will not affect it, as, indeed, such last-named motion cannot on account of the fulcrum i' . The lever I has a vertical rod, J, passing through an orifice in said lever, which is preferably quite broad, the rod being expanded beneath the lever into

a cross-piece, j^3 , (shown in Fig. 8,) from which two guides, j^4 , extend vertically upward. The lever I, working upon this rod J, moves with it the lever H and its support h' , (see Figs. 1, 5 3, and 4,) which is also attached to and supported by said lever I. The upper part of the rod J is attached to the lever H by the pin h^3 in the extremity of said lever, passing through the slot j^2 in the said rod. It is 10 also (see Fig. 2) enveloped by a spiral spring, j , compressed between the undersurface of the lever H and a stud or shoulder on the rod J above the lever I. The lever H, above referred to, is on the top of the bridge C^2 , (see 15 Figs. 1, 2, and 4,) and is fulcrumed at h in the aforesaid support h' . The needle-arm now descending, the needle makes a stitch through the cloth a short distance from the edge of the button-hole. The lever-arm R is lowered by 20 the descending needle-arm, and, as previously described, the disk N is rotated in a direction opposite to that in which it last rotated. This motion does not, however, in any way affect the cylinder O on account of the tooth P preventing its retraction. The needle-arm now ascends and the plate C is returned to its former position, throwing the feed-plate U from the slide T, thus bringing the center of the slot y' toward the needle-hole a^3 , so that the needle-hole will lie just beyond the edge of the button-hole in the goods. This motion of the plate C does not affect the gear D^2 , as the dog G, when retracted, loosens the hold of its point g upon the sleeve-flange E' , which, with the box, 30 mains stationary. (See Figs. 1 and 4.) It (the dog) is retracted to its original position in order that it may again operate the sleeve-flange E' when thrown to the right by the retracting-spring C^5 , coiled around the sleeve C^3 , and which 35 extends downward to the upper surface of the box F. This spring C^5 is attached to the bridge C^2 and box F, and acts so as to throw the box F in a direction the reverse of the arrow, Fig. 7, when the dog G is thrown in that direction. 40 The dog G may be stopped in its retraction by the stop-pin c^3 in the plate C, the spring C^5 keeping the dog G against that end of the closed slot l^3 which is nearest the needle, except when prevented from so doing by said stop-pin c^3 . As the needle now descends it makes 45 a stitch just over the edge of the button-hole, which, in connection with the other similar stitches, forms the binding on the edge of the hole. The operations above described are now 50 repeated, the stitching gradually approaching the curved or circular end of the button-hole, around which it passes, guided by the curved portion of the groove u^5 , and then advances along the other side of the hole until the end 55 of the hole is reached. The cam-lever k^4 , which is supported and journaled upon the pin k^5 , Figs. 2, 3, 4, and 19, is now elevated, and by bearing against the pin k , (to which it is connected by its fulcrum-pin k^5 , passing through 60 the slot k' in the plate K, and having a head beyond the cam k^4 to hold said cam k^4 in posi-

tion against the plate K,) and being connected by said pin k^5 to the vertical slide k^3 , raises with it said vertical slide k^3 , which slides in the vertical groove formed by rabbets in the 70 sides of the plate K. This vertical slide k^3 is situated between the plate K and the rear vertical wall of the bridge C^2 . The aforesaid pin k is fastened to the plate K at its outer side, near its lower end, said plate K being attached 75 to the plate C at the end of the bridge C^2 , Fig. 4. The cam-lever k^4 is also provided with a handle, k^6 , Figs. 3 and 18. The vertical slide k^3 , being operated upon and raised as heretofore described, forces up one end of the lever 80 H, which elevates the stem D, thereby withdrawing the pin d^3 from the groove u^5 and the teeth of the gear D^2 from meshing with the teeth u^7 of the plate u^6 . Elevating one end of the lever H depresses the other, forcing downward the rod J, whose notch j^5 , cut in the center of the cross-piece j^3 , Fig. 8, fits over the guide plate V, Fig. 5. As the pin d^3 is withdrawn from the groove u^5 and the rod J grasps the guide-plate V, the feed-plate U 90 is moved from side to side by the rod J instead of the pin d^3 . It will be remembered that the rod J is moved by the lever I, Fig. 4, and the lever I has a reciprocating lateral motion imparted to it by being fulcrumed at i , and by 95 receiving a reciprocating lateral impulse from the stem D, Fig. 4, which latter receives a lateral reciprocating motion through the plate C, which is reciprocated obliquely across the length of the plate A by the arm b^3 of lever L, 100 pivoted to the pivot b^4 , located on the edge of the sliding plate C, which in turn is kept in line by the slots c and guiding-pins c' , as has heretofore been fully described. The gear D^2 no longer meshing with the rack u^7 , the feed-plate U has now imparted to it a reciprocating lateral motion only. As the lateral motion of the rod J is greater than that of the pin d^3 , and as this motion is applied to the feed-plate U at 105 a point nearer its center of vibration—viz., the screw u —than before, the lateral motion of the feed-plate U is increased—in fact, the attachment is preferably arranged to make this motion just twice as great as its ordinary lateral motion. The attachment now vibrating, the stitching is 110 made transversely across the button-hole from outside to outside of the stitching previously made, thus forming the finish to the button-hole. This capacity to finish the narrow end of the button-hole, as well as to sew the round 120 end and sides of same, is, as has been previously mentioned, one of the objects of my invention. The rod J is depressed by raising the arm of the cam-lever k^4 , Figs. 3 and 4, which being pivoted to the vertical slide k^3 and bearing against the pin k , raises the slide k^3 , the top of which impinges against the end of the lever H, which is on the right-hand side in 125 Figs. 2 and 4, raises it, and the lever being fulcrumed at h , the raising of the right-hand end of said lever H depresses its other end, which in turn depresses the rod J. The spring 130

j and the slot *j*² are provided for the purpose of permitting the end of the lever *H* to be depressed when the notch *j*⁵ is not immediately over the guide-plate *V*. In this case some portion of the cross-piece *j*³ rests on the guide *V*, and as soon as the notch *j*⁵, by the continued operation of the sewing-machine, passes over the guide-plate *V* the spring *j* forces the rod *J* so that the notch *j*⁵ fits down upon and grasps the guide-plate *V*.

In the accompanying drawings (see Sheet 3, Figs. 13 to 17) a modification of my attachment is illustrated, which I will now briefly describe. Two disks, *M*, are provided, Fig. 17, placed beneath the plate *B* and connected by a crank-pin, 1. In Fig. 17 the upper disk, *M*, is removed to show the connection of the crank-pin 1 and slotted arm 2. Motion is imparted to either of the disks *M* or the disk *N* by the slide *T*, as heretofore described. The crank-pin 1 operates the arm 2 by working in a slotted extension or yoke, 10, transverse to the length of said arm, although the said arm 2 may be well operated by being pivoted directly to the crank-pin without the intervention of a slotted extension or yoke. This arm 2 is attached to the extension 3 of the lever *I*. In such a case the lever *I* is not fulcrumed at *i*, as heretofore described, but on and at the stem *D*. Thus the lever *I* operates the plate *C* and appendages, instead of the plate *C* operating the lever *I*. The device for rotating the stem *D* is changed, the stem *D* being provided with a gear-wheel, 4, keyed to it by a projection fitting in a slot in the edge of the stem *D*. This gear 4 meshes with a larger gear, 5, which is turned in one direction by a dog, 6, similar to the dog *G*, heretofore described. This dog is operated by means of a loop, 7, projecting from the support *h*'. The amount of motion of the dog 6 and consequent amount of rotation of the gear 5 and stem *D* are regulated by the set-screw 8. As the distance between stitches depends upon the amount of rotation of stem *D*, this distance or length of stitch is regulated by the set-screw 8. In the ordinary form of the attachment the length of the stitch is regulated by means of the nut *l*', Fig. 1, the stitch being shortened by screwing the nut *l*' out, and the length of stitch and also its depth depend in general upon the distance of the pin *l*² from the center of the disk *M*, and this distance is regulated by means of the screw in the base of the pin *l*² and the slide *m*². (See Fig. 9.) By unscrewing the pin *l*² it and the slide *m*² can be moved toward or away from the center of the disk *M* the desired distance. A further modification in the operating devices is illustrated in Figs. 23 and 24. The gear-wheel *N* transmits its motion from the rack *T* in the usual manner, through the sleeve *O* and shaft *m*⁴, to disk *M* and set-screw *l*². The lever *I* is fulcrumed at *i*, as usual, but has a rear extension, *i*², between the extremity of which and the set-screw *l*² a link, *L*⁶, is secured, and motion thereby

imparted from the disk *M* to the lever *I*, the latter in turn operating the plate *C*, with the mechanism thereupon, and rotating the stem *D* through the support *h*', loop 7, dog 6, and gears 4 and 5.

My attachment for making button-holes is secured preferably by a device such as the holder *Z* and thumb-screw *A*². (See Figs. 11 and 12.) The holder *Z* consists of two upright portions or pillars united at their top by a curved arch. The lower extremity of one of these pillars is provided with a pin, *z*, extending vertically downward from the center of the bottom of said pillar, and from the lower extremity of the other pillar is a horizontal projection, *z*', provided with a slot, *z*². The mode of applying this holder is shown in Fig. 12. The pin *z* is inserted in a recess in the plate *A*, and the arch of the holder overarches feed-plate *U* and clamping-jaw *Y*. When the plate *U* and clamping-jaw *Y* are moved out for sewing the round end of the button-hole the arch will overarch not only the feed-plate *U* and clamping-jaw *Y*, but also the guide-plate *V*. The holder is rotated about the pin *z* as a center until the slot *z*² is over the gage-hole of the top plate proper of the machine, (see Fig. 18,) where the holder is secured by a thumb-screw or other appropriate means. On account of the needle-plate of most sewing-machines being elevated above the top plate, and because part of my attachment through which the needle passes rests on the needle-plate, and because it is necessary that the other end of the attachment be elevated above the top plate the same distance that the needle-plate is, I have provided an adjustable screw, *A*³, (see Figs. 1 and 10,) having in its lower end a flanged base, *A*⁴. The screw *A*³ is adjusted in the plate *A*, so that when the base *A*⁴ rests on the top plate of the machine the end of the plate *A* is elevated to its proper position. The jam-nut *A*⁵ is now screwed down and secures the screw *A*³ in its position. This position will not have to be changed until the attachment is used on a different machine. The screw *A*³ is hollow, and through it the screw *A*² passes loosely and screws into the top plate of the machine, securing the attachment by its pressure on the top screw, *A*³. When the attachment is secured to the machine the arm *R*, Fig. 1, is attached by any appropriate means to the needle-arm and is vibrated by it.

Having described the operation and construction of my attachment, together with its mode of attachment to a sewing-machine, what I claim as new and of my invention, and desire to secure by Letters Patent, is—

1. In a button-hole attachment, means whereby only the upward travel of the needle-bar shall impart motion to the attachment, while retaining a positive connection between the needle-bar and the attachment, said means consisting of the slide-rack *T*, gear *N* *n*', cylinder *O* *O*³, and ratchet-teeth *O*² *P*, in combination with convenient means for communicat-

- ing the movements of the needle-bar to slide T, substantially as and for the purposes specified.
2. The combination of standard Q, levers 5 R S, rod S', slide-rack T, gear N n', cylinder O O³, and ratchet-teeth O² P, substantially as and for the purposes specified.
3. In a button-hole attachment, the combination, with slide-rack T, gear N n', cylinder 10 O O³, and ratchet-teeth O² P, of the levers R S and rod S', substantially as and for the purposes specified.
4. In a button-hole attachment, the combination, with suitable means for transmitting 15 motion to the goods from the upward travel only of the needle-bar of the sewing machine, of crank plate or disk M, pin l², lever L l' b³, pivoted to plate B, sliding plate C c b⁴, adapted to slide on plate B c', stem D d³, and feed- 20 plate U u⁵, substantially as specified.
5. The combination of crank plate or disk M, pin l², lever L l' b³, pivoted to plate B, sliding plate C c b⁴, adapted to slide on plate B c', stem D d³, and feed-plate U u⁵, substantially as and for the purposes specified.
6. The combination of disk M, pinion n, disk N n', cylinder O, provided with grooves O³, ratchet-teeth O² P, and connecting-shaft m⁴, substantially as and for the purposes specified.
7. The combination, with disk M and mechanism intermediate between same and the feed-plate, of the attachment for enabling the disk M to impart a lateral movement to the feed-plate, of means for regulating the amount of motion transmitted by the disk M to the plate C, through the plate C to the feed-plate of the attachment, said means consisting of the slide m², dovetailed into the groove m' in the disk M, and the binding-screw l², substantially as 40 described.
8. The combination, with the lever L l' b³ and disk M, of means for regulating the amount of motion transmitted to the plate C, and by the plate C to the feed-plate of the attachment, said means consisting of the slide m², dovetailed into the groove m' in the disk M, and the binding-screw l², substantially as described.
9. In a button-hole sewing attachment, means for producing an oblique movement of 50 the feed-plate, consisting essentially of slotted rod L' l³, dog G g, the plate B, its screws c', the plate C, having the oblique slots c, reciprocating box F, flanged sleeve E E' e', stem D d' d³, gear D², and feed-plate U u⁷ u u'.
10. In combination with reciprocating box F, the retracting-spring C⁵, secured by one end to the box and by the other end to the stationary bridge C² on plate C, substantially as specified.
11. In combination with slotted rod L' and box F, the dog G, provided with screw-threaded end, and thumb-nut l⁴, whereby the amount of motion transmitted to the dog may be modified so as to regulate the longitudinal movement of the feed-plate, substantially as specified.
12. In combination with slotted rod L' l³, the dog G, provided with screw-threaded end, and the thumb-nut l⁴, stop-pin c³, whereby the amount of motion transmitted to the dog may 70 be modified so as to regulate the longitudinal movement of the feed-plate, substantially as specified.
13. In combination with sliding rack T, the guide-flange a b' and plate A, B, and Q', substantially as and for the purposes specified.
14. In combination with the base-plate A of a button-hole attachment, the hollow adjusting-screw A³ A⁴ and jam-nut A⁵, substantially as and for the purposes specified.
15. In combination with the base-plate A of a button-hole attachment, the clamping-jaw Z z z' z', substantially as and for the purposes described.
16. The combination of the spindle D and 85 pinion D², the lever H h², fulcrumed to standard h' upon lever I, and means by which the spindle may be elevated, so as to be disengaged from the feed-plate, substantially as and for the purposes specified.
17. In combination, the sliding plate C C', that carries spindle D, and the slotted lever I i', fulcrumed on plate B at i, with suitable mechanism for connecting the free end of said lever with or disconnecting it from the feed-plate U, substantially as described.
18. In combination with the spindle D and pinion D², the lever H h², fulcrumed to standard h' upon lever I, slide k³, cam-lever k⁴, and fulcrum k, by means of which the spindle may 100 be elevated so as to be disengaged from the feed-plate, substantially as and for the purposes specified.
19. In combination, the feed-plate U, with its rack u⁷, spindle D, pinion D², spring d, secured between the shoulder upon the spindle and the under surface of bridge C², and adapted to force the spindle and pinion into contact with the feed-plate, substantially as described.
20. In combination, the feed-plate U, with its rack u⁷, spindle D, pinion D², lever H, bridge C², and spring d, thumb-nut d⁴, having a threaded connection with the upper end of the spindle and adapted to receive the pressure of lever H when operated to elevate the spindle, and to furnish a means for regulating the extent of the downward movement of the spindle, substantially as described.
21. In combination, the spindle D, lever I, standard h', lever H and means for elevating it, rod J j² j³ j⁵, spring j, feed-plate U, with its rack u⁷, and guide V v', substantially as and for the purposes specified.
22. In combination, the spindle D, sleeve E, lever I, standard h', lever H and means for elevating it, rod J j² j³ j⁵, spring j, feed-plate U, with its rack u⁷, and guide V v', substantially as and for the purposes specified.
23. In combination, the spindle D, sleeve E, and sleeve-axis C', lever I, standard h', lever H and means for elevating it, rod J j² j³ j⁵, spring j, feed-plate U, with its rack u⁷, and

guide V v' , substantially as and for the purposes specified.

24. In combination, the feed-plate U, with its rack u' , spindle D, pinion D², lever H, spring d, bridge C², thumb-nut d⁴, and washer d⁵, substantially as shown and described.

25. In combination with feed-plate U u' , accompanying guide-plate V v' , spindle D d³, pinion D², and plate C C', bridge C², the lever I, standard h', and lever H, spring d, nut d⁴, slide k³, cam-lever k⁴, fulcrum k, rod J j² j³ j⁵, and spring j, all combined to operate substantially as and for the purposes specified.

26. In combination with lever I, standard h', lever H h³, and feed-plate U and guide V v' , the rod J j² j³ j⁵, and spring j, combined to operate substantially as described, and for the purposes specified.

27. In combination with spindle D d³, adapted to be operated obliquely by plates C C', in the manner shown, and the pinion D², adapted to be rotated through the medium of dog G, as shown, the feed-plate U, having slot-and-pin connection u u', with button-hole-shaped rack u⁷, and correspondingly-shaped groove u⁵, to operate substantially as and for the purposes specified.

28. The combination of lever R, lever S, rod S', slide-rack T, gear N n', cylinder O O³, ratchet-teeth O² P, crank plate or disk M, pin l', lever L l' b³, pivoted to plate B, sliding plate C c b⁴, adapted to slide on plate B c', stem D d³, and feed-plate U u⁵, substantially as and for the purposes specified.

29. The combination of lever R, lever S, rod S', slide-rack T, gear N n', cylinder O O³, ratchet-teeth O² P, crank plate or disk M, pin l', slotted rod L' l', dog G g, reciprocating box F, flanged sleeve E E' E², stem D d' d³, gear D², and feed-plate U u' u u', substantially as and for the purposes specified.

30. The combination of lever R, lever S, rod S', slide-rack T, gear N n', cylinder O O³, ratchet-teeth O² P, crank plate or disk M, pin l', lever L l' b³, pivoted to plate B, sliding plate C c b⁴, adapted to slide on plate B c', slotted rod L' l', the dog G g, thumb-nut l⁴, reciprocating box F, flanged sleeve E E' E², stem D d' d³, gear D², and feed-plate U u' u u', substantially as and for the purposes specified.

31. The combination of lever R, lever S, rod S', slide-rack T, gear N n', cylinder O O³, ratchet-teeth O² P, crank plate or disk M, pin l', lever L l' b³, pivoted to plate B, sliding plate C c b⁴, adapted to slide on plate B c', stem D d³,

feed-plate U u⁷, lever H h³, standard h', spring C⁵, spring d, nut d⁴, means for elevating rear end of lever H, said means preferably consisting of slide k³, cam-lever k⁴, fulcrum k, guide V v', rod J j² j³ j⁵, and spring j, substantially as and for the purposes specified.

32. The combination of lever R, lever S, rod S', slide-rack T, gear N n', cylinder O O³, ratchet-teeth O² P, crank plate or disk M, pin l', lever L l' b³, pivoted to plate B, sliding plate C c b⁴, adapted to slide on plate B c', slotted rod L' l', dog G g, thumb-nut l⁴, reciprocating box F, flanged sleeve E E' E², stem D d' d³, gear D², feed-plate U u' u u', lever H h³, standard h', spring d, spring C⁵, nut d⁴, means for elevating the rear end of lever H, said means preferably consisting of slide k³, cam-lever k⁴, fulcrum k, guide V v', rod J j² j³ j⁵, and spring j, substantially as and for the purposes specified.

33. The combination of a support, as Q Q', lever R, lever S, rod S', slide-rack T, gear N n', cylinder O O³, ratchet-teeth O² P, crank plate or disk M, and mechanism for communicating to the feed-plate U a transverse reciprocating motion, and the dog G g, reciprocating box F, sleeve E E', stem D d' d³, gear D², and feed-plate U u' u u', substantially as and for the purposes specified.

34. The combination of a support, as Q Q', lever R, lever S, rod S', slide-rack T, gear N n', cylinder O O³, ratchet-teeth O² P, crank plate or disk M, and mechanism for communicating to the feed-plate a transverse reciprocating motion, and the dog G g, reciprocating box F, sleeve E E', stem D d' d³, gear D², and feed-plate U u' u u', and mechanism for elevating the spindle and causing the latter to be disengaged from the feed-plate and its said rack, substantially as and for the purposes specified.

35. In a button-hole sewing attachment, means for producing an oblique motion of the feed-plate, consisting essentially of the plate B, its screws or studs c', the plate C, having the oblique slots c, mechanism by which the plate C is reciprocated, stem D d' d³, gear D², and feed-plate U u' u u', and mechanism connecting said stem and feed-plate, substantially as and for the purposes specified.

SPAULDING CUTLER.
